UNITED STATES PATENT OFFICE

RALPH RAGAN, OF ATLANTA, GEORGIA

HEDDLE FRAME FOR LOOMS

Application filed May 24, 1930. Serial No. 455,414.

My present invention relates to the construction of heddle frames for looms, and to novel means for supporting the heddle bars intermediate their ends.

One of the principal objects of this invention is to provide improved means in a heddle frame for supporting the heddle bars intermediate their ends in such manner as to securely lock the bars against any motion whatsoever at the point of support and relative to the frame to thereby reduce to a minimum the breakage of the bars at that point, which means will, however, permit the bars, by means operable from the end of the frame to be readily locked and unlocked with respect to the frame when desired without disturbing the cloth on the loom and without requiring that the operator get down beneath the frame.

Another object of the invention is to provide a supporting means for the heddle bars including a clamp movable to locking and unlocking positions by eccentrics operable from one end of the heddle frame, and to provide for the locking clamps to be maintained automatically locked even though wear should take place.

A further object of the invention is to provide a heddle frame construction in which the frame members are separable, while the frame is in place on the loom, so that a new piece may be assembled on the frame to replace a broken one without requiring the removal of the frame from the loom, and without requiring the redrawing and re-tying of the warp.

A further object of my invention is to provide a construction in which the locking device in combination with the heddle bar support constantly exerts a clamping action on the heddle bars to thereby reduce to a minimum the possibility of wear, or of crystallization, and to add the cross sectional supporting strength of the heddle bars to the normal strength of the cross members of the supporting frame.

With these and other objects, which will become apparent as the description proceeds, the invention resides in the construction,

combination and arrangement of parts hereinafter more fully described and claimed.

In the drawings, which illustrate one of the forms that the invention may take,—

Figure 1 is a view in perspective, parts 55 being broken away, of the heddle frame with the supporting and locking devices, and showing the means of operating the locking devices from the end of the frame.

Figure 2 is a fragmentary side elevational 60 view of a corner of the frame.

Figure 3 is a plan view of the corner shown in Figure 2, partially in section.

Figure 4 is a transverse vertical section 65 through the top member of the frame showing the heddle bar support and clamp in elevation and in locked position.

Figure 5 is a view similar to Figure 4, showing the heddle bar support in unlocked position.

Figure 6 is a vertical sectional view taken approximately along the line 6—6 of Figure 4.

Figure 7 is a side elevational view of the parts shown in Figure 6, partially broken 75 away.

Figure 8 is a horizontal sectional view taken through one of the side members of the frame above the heddle bars.

Figure 9 is a view in elevation of a portion of the locking rod showing one of the eccentrics thereon.

Figure 10 is a view in section through one of the locking rods showing an eccentric thereon.

Referring more particularly to the drawings, the heddle frame includes top and bottom cross pieces or rails 1, and side members or rails 2. These are preferably made of tapered channel section metal. The ends 90 of the rails 1 are reduced, and tapered, as shown in Figures 2 and 3, so that the sides of the rails 1 have shoulders 1^a which fit squarely against the edges 2^a of the side rails 2 of the frame, with the tongues 1^b formed 95 on the closed side of the channel sections of rails 1, fitting snugly into the tapered channel sections of the side rails 2, and with the ends of such tongues abutting squarely 100 against the bottom faces of the channel sec-

tions of the side rails 2. Dowel pins 5 are driven through the side rails adjacent their ends into the ends of the closed sides of the channel sections of rails 1. Near the ends of the rails 1, pins 3 are passed transversely through their sides, these pins receiving the eyes of bolts 4, the outer threaded ends of which pass through openings provided in the side rails 2, and receive nuts and lock washers, which nuts upon being turned up, draw the rails 1 tightly and squarely against the side rails 2, to thereby maintain the frame in rigid squared condition.

The heddle bars 6 are arranged within the frame near the top and bottom rails 1, extending at their ends through slots cut in the bottoms of the channel sections of side rails 2. The heddles illustrated at 18, are mounted upon these heddle bars.

Means are provided for supporting and locking the heddle bars at points intermediate their ends, such means being provided for the lower and upper sets of bars. A description of the locking means for the upper bars will be sufficient, the locking means for the lower bars being similar in construction, but reversed as to position. While only one locking device is illustrated for each set of bars, it will be understood that as many may be used throughout the width of the frame as will be found desirable. This supporting and locking means includes the fixed clamp support 7, the sliding lock clamp 8, the locking rod 9, having the eccentric 12 mounted thereon, and locking handle 16.

The support 7, throughout the vertical width of the heddle bars, is of the width of the distance between the heddle bars when the latter are in locked position, so that the heddle bars abut throughout their width against the side edges of the main body portion of the support 7. This support at its outer end is bent over and fitted against and secured to the top rail 1. Near its inner end, at approximately the level of the inside edges of the heddle bars, the support 7 is provided with projections or ears 14, having edges 14^a sloping upwardly and outwardly to a distance greater than the thickness of the heddle bars, so that the inner edges of such bars rest on bevelled faces which tend to clamp them against the lateral edges of the support 7.

The lock clamp 8 is of a width slightly narrower than the body portion of the support 7, and consequently than the distance between the heddle bars, and this clamp is slidably mounted on the support 7 by means of rivets 11 carried by the support and which pass through the slot 10 which extends longitudinally of the clamp 8. The slot is of such width as to snugly receive the shanks of the rivets without permitting sidewise movement of the clamp 8, and is of such length as not to limit the movement of the clamp 8 longitudinally of the support 7, within the range of

adjustment of the clamp. The clamp 8 is provided with projections or ears 15, which overlie the outer or upper edges of the heddle bars 6, in opposition to the ears 14. And the ears 15 have their bottom edges curved outwardly and downwardly to provide cam surfaces 15^a, which engage the outer edges of the heddle bars when the clamp is forced inwardly or downwardly, to thereby impart a downward and inward thrust on the heddle bars.

The clamps are operated through the locking rod 9, which passes through and has a bearing on the fixed support 7, and on each side rail 2, such locking rod being suitably secured against endwise movement. In the plane of the clamp 8 an eccentric 12, preferably circular, is welded on the rod 9, being mounted off-center with respect to the rod as shown. This eccentric works in the slot 13 provided in the lock clamp 8. The position and arrangement of the slot and eccentric is such that when the throw of eccentric 12 is in a vertical raised position, the clamp 8 is in raised position and the ears 14 and 15 on the support and clamp, respectively, separated sufficiently to allow of the heddle bar 6 being drawn outwardly away from the support and over the sloping or leveled edges 14^a without interference. The purpose of this is to enable the heddle bars to be pulled away from their intermediate support to the position, for instance, indicated in dotted lines for one of the heddle bars in Figure 5, in order that the heddles may be slipped along the bars past the support. The bars 6 are slightly bowed inwardly, however, so that when they are released from a pulled out position, they will immediately return to a position against the lateral edges of the support 7, and rest at their lower edges on the inclined edges of the ear 14.

From the unlocked position of Figure 5, a turning motion of the rod 9 imparted by means of the handle 16 moves the eccentric around and downwardly against the inner edge of the slot 13, thus lowering the clamp 8, and moving its ears toward the ears 14 on the support 7. The cam surfaces 15^a striking the edges of the bar 6, force them inwardly against the edges of the clamp 7 and downwardly into binding engagement with the inclined surfaces 14, thus providing a bearing at each edge and across one broad side of the heddle bars. This locked condition is reached normally before the eccentric 12 has completed a half turn, so that a reserve of adjusting movement is maintained to compensate for any wear which may take place at the point of support, and in order to make the reserved clamping force available at all times the eccentrics are mounted on the rod at such angles that the one furthest from the operating handle will lock its clamp first, the rod having to be subjected to a torsional

strain before the next eccentric locks its clamp. In this manner, there will be enough power in the spring torsion of the rod between eccentrics, or between an eccentric and the handle, to keep the supports automatically locked even though some wear should take place.

The heddle bars 6 at their ends projecting beyond the side rails 2 of the frame are bolted together, a spacer means or guide 17 being provided on the bolt which is slightly less in length than the distance between the slots in the side pieces through which the bars pass. Thus, when the bolts are tightened the outer ends of the heddle bars are bent slightly toward each other, and clamped against the edges of the slots through which they pass, thus giving a bearing throughout the breadth of the bars between them and the side rails 2 of the frame, the friction of which will prevent any relative motion from beginning at this point, to thereby eliminate wear, even though the frame may be constructed of semi-soft material.

The handle 16 may be made of spring metal and may normally catch in between the ends of the heddle bars when the clamp is locked, to thereby maintain the locking rod in locked position. To turn the handle, it may be sprung out to clear the ends of the heddle bars. The handle may be fitted hexagonally on the rod (as at 9^a, Fig. 1) in order to give several different stopping places for the movement of the rod, and may be secured in position by a nut and lock washer. To change the stopping place of the rod, the nut may be loosened, the handle changed to the desired angle, and the nut may then be re-tightened.

From the foregoing it will be observed that the frame is so constructed that there is no possibility of a projecting surface coming into the path of a frame next to it, an advantage over steel heddle frames heretofore provided, and that no screws are used which could work loose and project beyond the frame, and further that there is no necessity of weakening the heddle bars by drilling holes through them, in order to clamp them against the heddle support. It will also be noted that there is no opportunity for the heddle bar supporting members to work loose. The construction is such that the common cause of wear and crystallization of the steel heddle bars is eliminated, due to the fact that the locking device in combination with the heddle bar support, constantly exerts a clamping action on the steel heddle bar, thereby eliminating wear and possibility of vibration such as might cause crystallization. Furthermore, through the medium of the locking device which maintains the heddle bars in constantly clamped condition, the cross sectional supporting strength of the heddle bars is added to the normal strength of the main cross pieces of the heddle frame.

I have found that in the process of weaving, especially on heavy grades of cloth, that with a frame constructed according to my invention, it is possible in case of frame-breakage while weaving, to replace the broken frame with a new one, without removing the heddle bars or heddles. This may be done by unlocking the heddle bars and removing the side of the frame opposite the locking handles, after loosening the necessary frame and heddle bar bolts and nuts, and then removing the remaining assembled portion of the frame constituting the top and bottom rails and remaining side rail, then slipping the replacement comprising a new side rail with assembled top and bottom rails in from the side of the loom and bolting the heddle bars with their heddles on them in their normal position, then connecting the opposite replacement side rail with the heddle bars bolted in position to the assembled replacement, ready to continue weaving after relocking the heddles. The heddles with their heddle bars can be supported by the warp during this replacement operation. If desired, the heddle bars may be temporarily tied up to the cross bar of the loom.

This replacement is not only much simpler than having to redraw and retie the warp, but also prevents the formation of a bad place in the finished piece of goods.

I may desire, in frames to be used on heavy grades of cloth, particularly, to additionally brace the frame and the clamps vertically. This I may do by connecting the clamp supports 7 with a bar or strip 19, of such size as to fit in between adjacent heddles, the ends of the bar or strip being bolted or otherwise secured as at 20, to the clamp supports 7. Such brace 19 not only aids in preventing relative movement of the top and bottom rails, but also aids in rigidifying the clamp supports.

It will be understood that while the invention has been illustrated in connection with double heddle bars, it is equally applicable to a frame in which single heddle bars are used, and that while the parts may be made of steel, hardened, if desired, other suitable material may be used. It will also be understood that the invention is capable of being embodied in other forms than the one which has been chosen for illustrative purposes, without departing from the invention or the scope of the claims.

Having thus described my invention what I claim as new and desire to secure by U. S. Letters Patent is:—

1. A heddle frame comprising end rails and side rails, all formed of tapered channel section metal, the ends of the end rails being provided with tongues tapered to fit the channels of the side rails and being provided with shoulders abutting against the edges of the

channels of the side rails, dowels inter-engaging the side rails and the ends of the end rails, pins extending transversely through the channel sides of the end rails, and eye bolts mounted on said pins and extending through the side rails and provided with nuts on the outside of the side rails for drawing the side rails and end rails together.

2. A corner construction for heddle frames comprising a side and an end rail, formed of channel section metal, the end of one rail being reduced to fit the channel of the other and being provided with shoulders abutting against the edges of the channel of the other; a pin extending transversely of one of the rails, and eye bolts mounted on the pin and extending through the other rail and provided with means engaging the other rail for drawing the rails together.

20 3. A heddle frame comprising end and side rails arranged in rectangular relationship, such rails being formed of channel section metal and being provided with inter-engaging shoulders and channel edges for retaining the frame in rectangular condition, and binding means between the end and side rails, anchored as to one set of rails, and inter-engaging with the other set of rails for drawing the end and side rails together and maintaining them in such position.

25 4. A heddle frame comprising end and side rails, pins carried by the end rails, and eye bolts anchored on the pins and having nuts engaging the side rails for removably clamping the end and side rails together.

30 5. A heddle frame comprising an end and a side rail, a heddle bar support carried by the end rail, including locking means provided with an actuating handle arranged on the outside of the side rail, heddle bars adapted to be engaged by said support and extending at their ends through the side rail, said actuating handle adapted to be engaged between the ends of the heddle bars for maintaining the heddle bar support in locked condition.

35 6. A heddle frame comprising a fixed clamp support and a movable lock clamp, heddle bars adapted to be clamped and released by relative movement of the lock clamp and support, an operating rod having means co-operating with the lock clamp for moving the latter with reference to the clamp support, and a handle for operating the rod adapted to be engaged between the ends of the heddle bars for maintaining the support in locked position and to be disengaged from there-between for operating the rod to unlock the clamp.

40 7. A heddle frame comprising a heddle bar support having a movable lock member for locking and unlocking the support, heddle bars adapted to be clamped and unclamped against the support by the movement of such lock, a rod for actuating the lock member, a

handle carried by the rod adapted to engage between the heddle bars for maintaining the clamp in locked condition, and an adjustable connection between the handle and rod whereby the position of the handle radially of the rod may be varied.

45 8. A heddle frame comprising a side rail, heddle bars extending at their ends therethrough, a bolt extending through the ends of the heddle bars beyond the side rail for drawing the extended ends of the heddle bars toward each other, and spacer means on the bolt between the heddle bars for limiting the movement of their projecting ends toward each other.

50 9. A heddle frame comprising a heddle bar support including a fixed clamp secured to one of the rails and having projecting ears provided with beveled faces adapted to engage the edges of the heddle bars, a slideable lock clamp mounted on the support provided with ears having beveled faces opposed to those of the support and adapted to co-operate therewith when the clamp is moved in one direction to force the heddle bars against the support, a rotary locking rod for the clamp, and eccentric actuating means between the rod and clamp for moving the clamp into locking or unlocking position when the rod is moved in one direction or another.

55 10. A heddle frame comprising an intermediate support for a heddle bar provided with an ear having a beveled face adapted to engage the edge of a heddle bar, a sliding lock provided with an ear having a beveled face opposed to that on the support and adapted to co-operate therewith to clamp the heddle bar throughout its width against the support when the lock is moved in one direction and to release the heddle bar when the lock is moved in an opposite direction, and means operable from outside the heddle frame for actuating the lock.

60 11. In a heddle frame, an intermediate heddle bar support comprising a fixed clamp secured to one of the rails of the heddle frame, and having projecting ears provided with beveled faces adapted to engage the edges of the heddle bars, a slideable lock clamp mounted on the support for movement with reference thereto and provided with ears having beveled faces opposed to those of the support and adapted to co-operate therewith to clamp the heddle bars throughout their width against the support when the lock clamp is moved in one direction and to release the heddle bars when the lock clamp is moved in an opposite direction, a locking rod, and co-operating means between the locking rod and clamp for actuating the latter when the locking rod is moved.

65 12. In a heddle frame, an intermediate heddle bar support, comprising a fixed support and a sliding lock movable with reference to the fixed support, the fixed support

- and sliding lock having co-operating means adapted to engage the heddle bars and clamp them against the support when the lock is moved in one direction and adapted to release the heddle bars when the lock is moved in an opposite direction, a rotary locking rod, and co-operating means between the locking rod and sliding lock for actuating the latter. 13. In a heddle frame, an intermediate heddle bar support, comprising a fixed support and a sliding lock movable with reference to the fixed support, the fixed support and sliding lock having co-operating means adapted to engage a heddle bar and clamp it against the support when the lock is moved in one direction and adapted to release the heddle bar when the lock is moved in an opposite direction, and means operable from outside the heddle frame for actuating the lock. 14. In a heddle frame, an intermediate heddle bar support, comprising a fixed support and a sliding lock movable with reference to the fixed support, the fixed support and sliding lock having co-operating means adapted to engage the heddle bars and clamp them against the support when the lock is moved in one direction and adapted to release the heddle bars when the lock is moved in an opposite direction, and a locking rod for actuating the lock and adapted to be placed under torsional strain for taking up wear. 15. In a heddle frame, an intermediate support for a heddle bar, comprising a fixed clamp and a lock clamp movable with reference to the fixed clamp, the fixed clamp and the lock clamp being provided with opposed beveled faces adapted when moved toward each other to engage a heddle bar and clamp it throughout its width against the fixed clamp, and means adapted to normally maintain the lock clamp under tension whereby to retain the heddle bar clamped in the support. 16. In a heddle frame, an intermediate heddle bar support comprising locking members movable with respect to each other, a rotary locking rod, eccentric actuating means between the rod and the locking members for actuating the latter, and means for actuating the locking rod. 17. In a heddle frame, an intermediate support for the heddle bars comprising a movable lock clamp, a movable locking rod, co-operating means between the locking rod and clamp for actuating the latter, and means located on the outside of the frame for actuating the rod. 18. A heddle frame comprising an intermediate support for the heddle bars including a fixed supporting member attached to one of the rails of the frame, and provided with ears having beveled faces adapted to engage the edges of the heddle bars, a sliding lock provided with ears having beveled faces opposed to those on the support and adapted to co-operate therewith to clamp the heddle bars throughout their width against their support when the lock is moved in one direction, whereby to add the cross sectional supporting strength of the heddle bars to the normal strength of the frame. 19. In a heddle frame, the combination with intermediate heddle bar supports, of heddle bars adapted to be locked to such supports, and extending at their ends through opposite rails of the frame, such bars normally being bowed inwardly toward each other, and at their ends beyond the rails being clamped together. In testimony whereof I hereunto affix my signature.
